UNITED STATES PATENT OFFICE.

NAFEW J. LLOYD, OF BUTTE, MONTANA.

CENTRIFUGAL SEPARATOR.

1,202,397

Specification of Letters Patent.

Patented Oct. 24, 1916.

Application filed October 7, 1914. Serial No. 865,564.

To all whom it may concern:

Be it known that I, NAFEW J. LLOYD, a citizen of the United States, residing at Butte, in the county of Silverbow and State of Montana, have invented certain new and useful Improvements in Centrifugal Separators, of which the following is a specification.

My invention relates to new and useful improvements in separators and, more particularly to centrifugal separators.

The primary object of the invention is the provision of a separator of simple construction which will effectually separate the lighter from the heavier materials.

A further object of the invention is the provision of means for regulating the discharge.

A still further object is the construction of a separator which may be easily cleaned.

With these and other objects in view the invention consists in the novel details of construction and arrangement of parts which will be more clearly understood from the following description and drawings, in which,

Figure 1 is a vertical section. Fig. 2 is a view in side elevation of the cap of the revolving bowl. Fig. 3 is a top plan view of the cap of the revolving bowl. Fig. 4 is a view in side elevation of the body portion of the revolving bowl. Fig. 5 is a top plan view of the basin and discharge for heavy particles. Fig. 6 is a top plan view of the cover of the stationary casing, and Fig. 7 is a detail of the bushing.

In the drawings, the numeral 1 indicates a base which may be secured to any suitable support and has a depending arm or bracket 2 having a vertical opening through the center thereof. A shoulder 3 is formed midway the ends of the vertical opening and a cap 4 is secured on the underside of the bracket 2 by means of the bolts 5 and receives a ball bearing 6 upon which rests a reduced end 7 of a vertical shaft 8. Between the shoulder on the shaft 8 and the shoulder 3 is received a packing ring 9. The upper end of the shaft 8 is forked, the purpose of which will be presently described and keyed upon the shaft is a small pinion 10 which meshes with and is operated by a large pinion 11 which is driven through any suitable power. The base 1 is provided with a plurality of vertical ribs 12 and a casing 13 is formed integral with the base and is provided with a plu-

rality of elongated openings 14, as clearly shown in Fig. 1 of the drawings. The casing 13 is provided at the top with a flange 15 having a plurality of vertical openings 16 60 therein.

The numeral 17 indicates the body portion of a bowl having a downwardly extending member 18 provided on the end with a tongue adapted to be received in the forked end of the shaft 8. A cap 19 is received in the bottom of the base and has an extension entering the base and overlying the meeting ends of the extension 18 and shaft 8. A bushing 20 is received between the lower 70 end of the casing 13 and the extension on the cap 19. The body portion 17 of the bowl is provided at the top with a plurality of circumferentially spaced openings 21 and the top is threaded interiorly. A cap 22 75 having the downwardly extending ribs 23 formed integral therewith is received in the top of the body of the bowl 17 and the ribs 23 extend downward into the bowl. The cap 22 is provided with the exterior threads 24 80 which engage the threads on the interior of the body of the bowl. This cap is also provided with a plurality of circumferentially spaced notches 25 which are adapted to be brought into registration with the openings 85 21 formed in the body of the bowl and entering the openings and notches are the bushings 26 having enlarged heads and central openings. The cap 22 is provided with the flared top, as shown at 27, the purpose 90 of which will be presently described.

Secured on the top of the casing 13 is a cover formed in two sections 28 and 29 as is more clearly shown in Fig. 6 of the drawings. When brought together the two sections are secured by means of bolts passing through the flanges 30 and the cover is secured to the body of the casing by means of bolts passing through lugs 31 and through the openings 16 formed on the flange 15 of 100 the casing. When the sections are brought together they form the central opening 32 and the sections are each provided interiorly with a flange 33 forming a concaved receptacle 34. The section 29 is provided with a spout 35, as is clearly shown in Figs. 1 and 6 of the drawings. This spout leads from the concaved receptacle 34 formed in the cover. The flared end 27 of the cap of the bowl 17 extends over the flange 33 when the 110 parts are assembled.

The numeral 36 indicates an inlet pipe

which extends through the opening 32 in the cover of the outer bowl, through the cap of the bowl 17, and to a point near the bottom of the bowl 17.

5 The bushings 26 are adapted to be provided with central openings of various diameters, whereby the separation of the heavier material from the lighter may be regulated.

10 Mounted within the receptacle is a basin or lining 37 the lower end of which is bent to form a channel 38 and the upper end of which is bent, as shown at 39, to closely fit and engage the wall of the receptacle and 15 the cover therefor. One side of the basin or lining 37 is cut away and bent to form a spout 40 which passes through one of the openings 14 in the casing 13.

Having fully described the detailed construction of my device it is thought that the operation will be clearly understood. The material to be separated is fed through the supply pipe 36 and is deposited on the bottom of the inner bowl 17. The bowl 17 is 25 adapted to be rapidly rotated through means of the gears 10 and 11 and as it is rotated the heavier particles will be thrown by centrifugal force toward the sides of the bowl and will rise and be discharged through the openings in the bushings 26 and deposited in the basin 37 from which they are discharged through the spout 40. The lighter particles will follow the ribs 23 formed on the cap 22 and will be carried toward the center of the bowl 17 and rise through the opening in the cap and over the flange 27. These lighter particles are deposited in the concaved receptacle or channel 34 and discharged 30 through the spout 35. By inserting bushings having openings of greater or less diameter the degree of separation may be regulated so as to discharge particles of greater or less weight therethrough.

I have constructed a separator which may be used for separating various articles and more particularly ores. It can equally as well be used in the separation of milk or other material.

45 When it is desired to clean the separator the sectional cover on the casing 13 is removed and the inner bowl 17 can then be taken out, the cap removed and the inner bowl 17 cleaned. The basin or lining 37 can also be readily moved for cleaning purposes.

Having fully described the invention what I claim as new and desire to secure by Letters Patent is:—

1. A centrifugal separator comprising a 60 bowl having screw threads formed on its interior at its open end and a plurality of openings extending through said bowl and through said screw threads, and a cap provided with screw threads for engaging said screw threads on said bowl and having a plurality of notches on its lower engaging

edge adapted to register with the openings in said bowl.

2. A centrifugal separator comprising a bowl having screw threads formed on its interior at its open end and a plurality of 70 openings extending through said bowl and through said screw threads, a cap provided with screw threads for engaging said screw threads on said bowl and having a plurality of semi-circular notches on its lower edge 75 for registration with the openings in said bowl, and a plurality of ribs formed on said cap and extending into said bowl.

3. A centrifugal separator comprising a bowl having screw threads formed on its interior at its open end and a plurality of 80 openings extending through said bowl and through said screw threaded portion, a cap provided with screw threads adapted to engage the screw threads on said bowl and 85 having a plurality of notches in its lower edge for registration with the openings in said bowl, and a plurality of bushings received in said openings and said notches.

4. A centrifugal separator comprising a 90 bowl provided with screw threads on its interior at its open end, a cap for said bowl provided with screw threads adapted to engage the screw threads on said bowl, and means for establishing communication 95 through said screw threaded portion of said bowl and said cap whereby a portion of the contents of said bowl may be discharged from the interior to the exterior of said bowl.

5. A centrifugal separator comprising a bowl having a plurality of circumferentially spaced openings, a cap having an opening therein connected to the bowl and provided in its lower edge with a plurality of circumferentially spaced notches adapted to register with the openings in the bowl, and bushings received in the circumferentially spaced openings and notches.

6. A centrifugal separator comprising a 110 bowl having a plurality of circumferentially spaced openings, a cap having a central opening connected to the bowl and provided on its lower edge with a plurality of notches adapted to register with the circumferentially spaced openings, hollow bushings received in the openings and notches, and a plurality of vertical ribs formed on the cap and extending into the bowl.

7. A centrifugal separator comprising a 120 stationary casing, a rotatable bowl provided with a plurality of circumferentially spaced openings received in the stationary casing, hollow bushings received in the openings, a cap having a central opening secured to the rotatable bowl, a flange formed on the cap adjacent the central opening, and a sectional cover secured to the stationary casing and engaging beneath the flange of the rotatable bowl.

8. A centrifugal separator comprising a stationary casing, a rotatable bowl having a plurality of circumferentially spaced openings received in the stationary casing, a cap having a central opening secured to the rotatable bowl, a flange formed on the rotatable bowl adjacent the central opening, a plurality of vertical ribs formed on the cap and extending into the bowl, hollow bushings received in the circumferentially spaced openings, a sectional cover secured to the stationary casing and engaging beneath the flange of the cap of the rotatable bowl, a discharge spout formed on the cover adjacent the central opening of the cap, a receptacle between the stationary and rotatable bowl and beneath the hollow bushings, and a discharge spout leading from the receptacle.
